CLAIM

The ornamental design for a postal receptacle, as shown and described.

DESCRIPTION

FIG. 1 is a front view of an embodiment of a postal receptacle assembly;

FIG. 2 is a top perspective view of the postal receptacle assembly of FIG. 1;

FIG. 3 is a left side view of the postal receptacle assembly of FIG. 1, the right side view being a mirror image of the left side view;

FIG. 4 is a top view of the postal receptacle assembly of FIG. 1;

FIG. 5 is a bottom view of the postal receptacle assembly of FIG. 1;

FIG. 6 is a back view of the postal receptacle assembly of FIG. 1;

FIG. 7 is a front view of a second embodiment of a postal receptacle assembly;

FIG. 8 is a top perspective view of a postal receptacle thereof;

FIG. 9 is a left side view of a postal receptacle assembly, the right side view being a mirror image of the left side view;

FIG. 10 is a top view thereof;

FIG. 11 is a bottom view thereof; and,

FIG. 12 is a back view thereof.
